(57) **CLAIM**

The ornamental design for a Z-closure member for mounting a vent cap on a raised seam roof, as shown and described.

DESCRIPTION

FIG. 1 is a front perspective view of the Z-closure member for mounting a vent cap on a raised seam roof showing my design;

FIG. 2 is a rear perspective view thereof with a filter installed, the filter being shown in broken lines;

FIG. 3 is a left side elevational view thereof with a filter installed;

FIG. 4 is a right side elevational view thereof;

FIG. 5 is a front elevational view thereof;

FIG. 6 is a rear elevational view thereof with a filter installed;

FIG. 7 is a top plan view thereof; and,

FIG. 8 is a bottom plan view thereof.

The broken lines are shown for environmental purposes only and form no part of the claimed design.
